(57) **CLAIM**

The ornamental design for a chair blanket, as shown and described.

DESCRIPTION

FIG. 1 is a front view of a chair blanket showing the new design;

FIG. 2 is a rear view thereof;

FIG. 3 is a right side view;

FIG. 4 is a left side view;

FIG. 5 is a top view;

FIG. 6 is a bottom view;

FIG. 7 is a front perspective view showing the chair blanket in an environment of use; and,

FIG. 8 is a rear perspective view showing the chair blanket in an environment of use.

The broken lines shown in the drawings illustrate environment and form no part of the claimed design.

1 Claim, 6 Drawing Sheets
